UNITED STATES PATENT OFFICE.

LEWICKI J. LEON, OF CHICAGO, ILLINOIS, ASSIGNOR TO L. J. LEON MFG. CO., OF CHICAGO, ILLINOIS, A CORPORATION OF ILLINOIS.

CATCH FOR BIRD CAGES.

Application filed June 12, 1922. Serial No. 507,790.

To all whom it may concern:

Be it known that I, LEWICKI J. LEON, a citizen of the United States, residing at Chicago, in the county of Cook and State of Illinois, have invented new and useful Improvements in Catches for Bird Cages, of which the following is a specification.

This invention relates to catches for releasably locking the cage-body and base of 10 a bird-cage together.

Among the objects of my invention is to improve the construction of bird-cage catches as will hereinafter more fully appear and in particular to provide a catch construction 15 adapted for circular bird-cages.

In the accompanying drawings—

Fig. 1 is a side elevational view of a bird-cage provided with catch members of my invention;

20 Fig. 2 is a horizontal sectional view taken on line 2—2 of Fig. 1;

Fig. 3 is an enlarged fragmentary top plan view of one of the catch members and the associated parts of the base and cage-body;

25 Fig. 4 is a vertical sectional view taken on line 4—4 of Fig. 3;

Fig. 5 is a perspective view of one of the catch members;

30 Fig. 6 shows another form of catch member; and

Fig. 7 is a vertical sectional view taken on line 7—7 of Fig. 6.

As illustrated in Fig. 1, the cage comprises a body 1 and a removable base or pan 2, both circular in form and with the top of the cage-body 1 dome-shaped, as shown. The base 2 is provided with an upright marginal wall 2^a which at its upper edge has an 35 inwardly extending annular flange 3 to provide a seat for the base ring 4 surrounding the lower open end of the cage-body 1 and to which the lower ends of the wires 5 extend and are secured, as shown in Fig. 4. The 40 flange 3 also supports the removable tray 6 carried by the base 2. The marginal portion of the tray 6 is between the flange 3 and the base ring 4, as shown in detail in Fig. 4.

To releasably lock the cage-body 1 and 50 base 2 together, I provide a plurality of catch members 7, 7 carried by the base 2 on the outside thereof and spaced apart circumferentially about the same, as shown in Fig. 2. The base flange 3 has a horizontal 55 top flange or portion 8 extending around the

same and offset upwardly a slight distance from the flange 3 with which it is integrally connected, as shown in Fig. 4. The annular recess thus formed makes an annular seat for the bottom of the cage-body 1 and causes 60 the upper face of the base ring 4 to be substantially flush with the top face of the flange 8.

As shown in the drawings, each catch member 7 has a flat body, semicircular in 65 shape and pivoted on the flange 8 by a pin 9. The flat body of the member 7 has a curved edge 10 on one side and a straight edge 11 on the other. Said straight edge 11 is a chord of the circle of which the curved 70 edge 10 is an arc, and the pin 9 is at the center of the latter. The pin 9 fastens the catch member 7 close to the inner annular edge of the flange 8, so that when the catch member 7 is in unlocked position its straight 75 edge 11 is substantially tangential to the inner annular edge of said flange 8, as shown in full lines in Fig. 3. By the construction described, the catch member 7 has two portions 12, 12 on opposite sides of the pivot pin 80 9 and, being mounted as shown, causes one of these end portions 12 to be rotated inward over the base ring 4 when the catch member is turned about its pivot pin, as shown in dotted lines in Fig. 3. Thus, the 85 catch member 7 will engage the base ring 4 when turned in either direction because there is a portion 12 on each side of the pivot pin 9 to engage this ring.

To facilitate turning the catch member 90 7, the same is provided with a finger piece 13 arranged above the same and substantially parallel thereto. Said finger piece 13 is integrally joined at its rear end with the body part of the catch member by a flange 95 14. This is at the straight edge 11 of the body part, as shown in Fig. 4. By this construction, the finger piece 13 extends across the top of the body part and is spaced above the same a sufficient distance to facilitate 100 grasping it and thus enabling the catch member to be readily and conveniently turned into and out of locking position.

The diameter of each catch member 7 is 105 such that it does not, whether locked or unlocked, project much over the outer edge of the flange 8. Moreover, the finger pieces 13 do not project beyond the curved edges 10 of their associated catch members 7. Thus, whether locked or unlocked, the catch mem- 110

bers 7 do not project outward beyond the base or pan 2 to strike against or catch in surrounding objects when the cage is handled or carried about. By making the catch members 7, 7 in the shape shown, they may be set close to the inner edge of the flange 8 and thus be kept within the outer edges of the base or pan 2 to gain the advantages mentioned and further enhance the general 10 appearance of the cage by making it free from unsightly projecting parts.

Moreover, the catches 7, 7 being distributed about the base or pan 2, as shown provides a fastening which holds the cage-body 1 and pan 2 properly together and gains a closed joint between the parts, thus adding to the neat and finished appearance of the cage. The catch members 7 extending above the flange 8, when open, serve to guide the lower end of the cage-body 1 to the seating flange 3, and moreover center the cage-body 1 and pan when applying one to the other. These members 7, 7 also, by projecting above the flange 8, prevent lateral displacement of the cage-body and pan 2. The members 7, 7 being mounted to rotate in the plane of the flange 8 and ring 4 permits making them relatively low and thus frees the cage of projecting parts.

30 In Figs. 6 and 7, I have shown another form of catch member. This is indicated by 7^a and is mounted on the flange 8 by a pivot pin 9^a and turned into and out of locking engagement with the base ring 4 of the cage-body, as before. The catch member 7^a differs from the one 7 heretofore described in that it has a locking notch or slot 15 opening outward through its straight edge 11^a, as shown in Fig. 6. This slot 15 is so made that it receives one of the cage wires 5 when turned into locking position engaging over the base ring 4, as shown in full lines in Figs. 6 and 7. At the inner end or base of this slot, there is a shallow recess 16 to accommodate the engaged cage-wire 5 and assist in locking it in said slot. When unlocked, the catch member 7^a has its straight edge 11^a tangential with the inner edge of the flange 8, as before, as shown in dotted lines in Fig. 6. To facilitate turning the catch member 7^a the same is provided with a finger piece 17 extending upright from the flat body of the catch member at one end of its straight edge.

55 While I have shown and described herein in detail catches for bird-cages of my invention, it is of course to be understood that the details of construction may be variously changed and modified without departing from the spirit and scope of my invention.

I claim as my invention:

1. A bird-cage, comprising a separable cage-body and base, said cage-body having a base member about its lower end, said base having a substantially upright surrounding

marginal wall provided at its upper end with an inwardly extending portion forming two upwardly facing flanges, one offset below the other to provide a seat for said base member, and catch members pivoted on the 70 other of said flanges in a manner to be turned in the plane thereof into and out of locking engagement with said base member.

2. A bird-cage, comprising a separable cage-body and base, said cage-body having 75 a base member about its lower end, said base having two upwardly facing flanges surrounding the same, one being below the other and extending inward to provide a seat for said base member, and catch members pivot- 80 ed on the other of said flanges in a manner to be turned in the plane thereof into and out of locking engagement with said base member, said catch members having arcuate slots to receive the adjacent wire of said cage-body. 85

3. A bird-cage, comprising a separable cage-body and base, said cage-body having a base member about its lower end, said base having a substantially upright surrounding marginal wall provided at its upper end 90 with an inwardly extending portion forming two upwardly facing flanges, one offset below the other to provide a seat for said base member, and catch members pivoted on the other of said flanges in a manner to be 95 turned in the plane thereof into and out of locking engagement with said base member, said catch members having flat body portions with straight edges, the latter clearing the base member of the cage-body when 100 turned into unlocked positions.

4. A bird-cage, comprising a separable cage-body and base, both circular in shape, said cage-body having a ring about its lower end, said base having two upwardly facing 105 annular flanges, one being below the other and extending inward to provide a seat for said ring, and catch members pivoted on the other of said flanges in a manner to be turned in the plane thereof into and out of 110 locking engagement with said ring, said catch members having substantially semi- 115 circular flat body portions with curved and straight edges, the latter being tangential to the inner edge of the flange on which said catch members are mounted when the catch members are turned into unlocked positions.

5. A bird-cage catch, comprising a sub- 120 stantially semicircular flat body portion adapted to be pivoted to the base of a bird- cage and be turned into and out of locking engagement with the lower part of the separable cage-body thereof, said body portion having a curved edge on one side and a 125 straight edge on the other, and a finger piece connected therewith and arranged above the same.

6. A bird-cage, comprising a separable cage-body and base, and catch members piv- 130

oted on the base outside of the cage-body in a manner to be turned in the plane thereof, said catch members being spaced apart about said base and having slots to receive the adjacent wires of the cage-body when the catch members are turned into positions to lock the cage-body and base together.

7. A bird-cage catch, comprising a body part to be pivoted on the base of a bird-

cage, said body part having a hook-shaped portion to engage one of the adjacent wires of the cage-body in turning the catch into position to lock the cage-body and base together.

In testimony that I claim the foregoing as my invention, I affix my signature this 6th day of June, A. D. 1922.

LEWICKI J. LEON.
